Des. 1671

Elmir J. Ney of Lowell, Mass.
Assignor to
The Lowell Manufacturing Company
Letters Patent No 1671 Dated Nov 11th 1862.

The schedule referred to in these Letters Patent and making part of the same.

To all whom it may concern

Be it known, that I, Elmir J. Ney of Lowell, in the County of Middlesex and State of Massachusetts, have originated and designed a new Pattern for Carpets or other fabrics, of which the following is a full, clear and exact description, reference being had to the accompanying drawings, making part of this Specification.

This design consists, chiefly, of series of figures composed of four hearts arranged about a centre from which radiate four arms, at right angles with each other.

Alternating with the before mentioned figures, are outline figures composed of a cross surrounded by a frame of dotted lines.

Des. 1671

The outline figures of one series are connected with those of the other, by small, dotted and solid blocks.

The colors employed for the different portions of the designs, may be varied to suit the taste and wish of the manufacturer.

Claim V

What I claim as my invention and desire to secure by letters, patent, is the design or pattern, for carpets or other fabrics, herein set forth.
